UNITED STATES PATENT OFFICE

JOHN WEIBRECHT, OF HOBOKEN, NEW JERSEY, ASSIGNOR TO THE KEUFFEL & ESSER COMPANY, OF HOBOKEN, NEW JERSEY, A CORPORATION OF NEW JERSEY

TAPE REEL

Application filed September 29, 1926. Serial No. 138,350.

My invention relates to reels and more particularly to reels for tape measures, the invention being directed chiefly to the casing of such reels.

5 Casings used for reels and particularly for reels for tape measures and used for similar purposes should be sufficiently strong to withstand the treatment ordinarily received by them, and it is desirable that they shall be 10 covered and that the casing and cover shall meet all requirements with respect to durability and appearance.

The object of the present invention is to provide a simple, efficient, attractive and 15 durable casing for tape reels and the like that may be readily manufactured without excessive expense.

Further objects and advantages of the present invention will appear from the following 20 description thereof taken in connection with the drawings wherein,

Fig. 1 is a sectional view of a tape reel embodying my invention,

Fig. 2 is a sectional view of the casing, 25 with parts broken away, taken on the line 2-2 of Fig. 1,

Fig. 3 is an enlarged view of a part of the cross sectional view shown in Fig. 1,

Fig. 4 is an enlarged view, with parts 30 broken away, illustrating the details of the means for securing parts of the casing together,

Fig. 5 is a broken view partly in section of a modification of the invention, and

Fig. 6 is a sectional view, with parts broken away, taken on the line 6-6 of Fig. 5.

In the embodiment of my invention, shown for the purpose of illustrating the same, in Fig. 1 to Fig. 4 inclusive, the casing 10 supports a drum 9 which may be of any configuration suitable to the winding up of a tape, chalk line or other article. The casing is generally cylindrical in form and comprises two sections or side members 11 and 12 that are composed of any desired material, such as a suitable metal, and joined together. Each of the side members or sections 11 and 12 is provided with or carries at its periphery a cylindrical flange and the flange carried 45 by one of the sections fits within and is held

in proper relation with the flange of the other side member or section. Thus the side member or section 12 is provided with the peripheral cylindrical flange 14 and the side member 11 is provided with or carries the cylindrical peripheral flange 13. The flange 13 includes a portion 13' that is of less diameter than the flange 14 and has an external diameter substantially equal to the internal diameter of the flange 14. The contracted portion 13' of the flange 13 is so proportioned that when the contracted portion 13' is inserted within the flange 14 the casing 10 will be provided with a peripheral groove 18 formed by the edge of the flange 14 and by the shoulder 8 which results from contracting the flange 13 to form the contracted portion 13'.

To the end that the side members or sections 11 and 12 may be readily and permanently joined, the flanges 13 and 14 are so constructed as to interlock, such interlocking being effected by merely forcing one flange into the other. Thus projections 16 are formed on the inner surface of flange 14 preferably by making indentations 16' on the outer surface thereof and cooperating openings 15 are formed in flange 13. The projections 16 are preferably made latch-shaped so that the edge of the flange 13 will slide over them and then the flange 13 will be held in place when the projections 16 snap into the openings 15. The flange 13 is so proportioned and the openings 15 therein are so located that when the projections 16 come into place in the openings 15, the edge of flange 13 will engage the inner surface of the side member 12 to the end that the side members 11 and 12 will be held in spaced relation by means of the flange 13. The projections 16 and the corresponding openings 15 are spaced at suitable intervals around the flanges 14 and 13. By providing notches in the flanges 13 and 14 an aperture or mouth 19 is provided in the casing for the tape or other article wound on the drum 9.

As shown in Fig. 5 the contracted portion of the flange of one side member that fits within the flange of the other side member

and may be made separate in which case the side members 11' and 12', as shown in Figs. 5 and 6, are each provided with a cylindrical peripheral flange having inward projections 28, and a ring 26, that corresponds to the contracted portion 13', is provided with openings 27 that engage the projections 28. In either the construction shown in Fig. 3 or the construction shown in Fig. 5 the parts 10 are firmly held together when once assembled. In the construction shown in Figs. 5 and 6 the ring 26 is not continuous and the peripheral flanges of the side members 11' and 12' are not continuous but are turned 15 in at 45, over the ends of the ring 26, and an aperture or mouth 19' is thereby produced and the ring 26 is held in place.

In either of the forms of construction above described the body of the casing is generally 20 cylindrical with a peripheral groove 18 and a mouth or aperture 19.

A covering for the casing may be of any suitable material such as leather or imitation leather or other flexible and durable substance of desired appearance. The covering is preferably made in two parts 17 and said parts lie upon the side members 11 and 12 or 11' and 12' and are held in place at the center of said member by rings 7 that extend 25 around the edges of the openings in the casing in which the drum 9 is mounted and are turned over the edges of the covering and of the side members, as by the spinning or bending. The side members and covering are 30 thus firmly clamped together by the rings 7 at the openings that support the drum 9. The outer edges of the covering material are folded around the edges of the casing and brought to position in the peripheral groove 18 of the casing. These outer edges are preferably secured to the casing as by suitable cement.

A strip 22 covers, conceals and protects the edges of the covering material 17 that lie in the groove 18. The strip 22 may be held in place in various ways but as shown its ends 22' are turned into the mouth or aperture 19 or 19'. The aperture 19 or 19' is provided with a mouth piece 21 that usually carries a 35 roller 20 and is provided with tongues 25 that are turned back against the ends 22' of the strip 22 and thereby assist in holding the strip 22 in place. The strip 22 may be of any suitable material that will conceal and 40 protect the edges of the covering 17 that lie in the groove 18 and that will present a suitable appearance. The strip 22, particularly when made of a ductile metal, will act, particularly when applied tightly, to bind the 45 edges of the covering material into the groove 18 and hold them there when its ends 22' are turned into the aperture 19.

From the foregoing it will be apparent that I have described a casing suitable for tape 50 reels and the like which may be readily con-

structed and which will be strong and durable and permanently assembled and which is provided with a cover that is well secured to the casing with its free edges protected; and since the strip 22 may lie in and fill the groove 18 the casing will be free of undesirable projections. It is to be understood that my invention is not limited to the details described but includes such variations and modifications as fall within the hereunto appended 75 claims.

What I claim as new and desire to secure by Letters Patent of the United States is:

1. In a tape reel, a side member having a cylindrical flange, a second side member, a cylindrical part fitting within said flange and connected to the other of said side members, said flange having latch-like inward projections and said cylindrical part having openings receiving said projections, whereby 80 said side members are permanently joined when said cylindrical part is forced into said flange.

2. In a tape reel, a casing comprising side members each having a peripheral right-angled flange, one of said flanges fitting within the other, and fastening means comprising cooperating parts respectively carried by 85 said flanges and held in fastening relation by the resilience thereof.

3. In a tape reel, a casing comprising disk-like side members each having a cylindrical flange, the flange of one of said members fitting within the flange of the other member, one of said flanges having projections and the other of said flanges having openings in which said projections engage, whereby 90 said members are joined by forcing one of said flanges into the other and thereby engaging said projections in said openings.

4. In a tape reel, a casing comprising side members each having a peripheral right-angled flange, one of said flanges fitting within the other, and fastening means comprising cooperating parts respectively carried by 95 said flanges and held in fastening relation by the resilience thereof and the flange of one of said members engaging the other of said members and thereby spacing said members.

In testimony whereof I have signed my 100 name to this specification.

JOHN WEIBRECHT.
